UNITED STATES PATENT OFFICE.

CHESTER ROACH, OF MINNEAPOLIS, MINNESOTA.

PUNCHING-MACHINE.

SPECIFICATION forming part of Letters Patent No. 351,340, dated October 19, 1886.

Application filed June 9, 1886. Serial No. 204,594. (No model.)

To all whom it may concern:

Be it known that I, CHESTER ROACH, of Minneapolis, in the county of Hennepin, State of Minnesota, have invented a new and useful Improvement in Punching-Machines, of which the following is a full, clear, and exact description, reference being had to the accompanying drawings, forming part of this specification, in which—

10 Figure 1 is a perspective view of a punching-machine embodying my improvement. Fig. 2 represents details of the two-part head or plunger.

15 My invention relates to certain improvements in punching-machines especially adapted for the use of tinners and sheet-metal workers; and it consists in the construction and combination of elements hereinafter described and specifically claimed.

20 To enable others skilled in the art to make and use my invention, I will proceed to describe the manner in which I have carried it out.

25 In the said drawings, A represents the main frame or casting of a punching-machine of any well-known and suitable construction. B represents the usual operating-lever, journaled in bearings in the front of the frame, and having its rear end attached to a spring, C, as shown in Fig. 1. Upon a ledge, a, projecting from the main frame, is swiveled or otherwise secured to rotate a standard, D, in the upper slotted end of which is fulcrumed the upper lever, E, by which power is applied to operate the 30 lever B and its adjuncts. The rear end of the lever B engages the head b of a threaded bolt, F, the shank of which also passes through the lever E, and is secured by suitable adjusting-nuts, as shown. From this description it is 35 evident that by swiveling the standard D, I am enabled to throw the lever in or out, as desired.

40 In the front portion of the main frame is located the plunger G, which carries the punch. This plunger is formed in two parts, d and e, connected together by screws f, whereby the section d may be removed when it is desired to take out a broken punch, or for any other similar purpose. The section e is provided 45 with ribs g, which engage grooves in the sides of the frame A, thereby forming guides in which the plunger vertically reciprocates during the movements of the machine. By reference to Fig. 2 it will be observed each of

the sections d e, which form the plunger, are 55 provided with semicircular grooves l, having threads corresponding with the size and pitch of the thread on the shank of the punch. This punch H is a steel punch, and has the usual punching-face and an integral threaded stem 60 or shank, which passes through the threaded opening formed by the grooves l, and at its extreme upper end is provided with a squared portion adapted to receive a wrench or equivalent tool, whereby the punch is adjusted within 65 the plunger until its punching-face is at the proper distance from the die m, as shown in Fig. 1.

Having thus described my invention, what I claim as new, and desire to secure by Letters 70 Patent, is—

1. In a punching-machine, the main frame A and operating-lever B, in combination with a standard, D, swiveled or otherwise secured to rotate upon the main frame, a lever, E, 75 fulcrumed within the slotted upper end of the standard, a connection between the rear ends of the said levers, and a reciprocating plunger carrying the punching-tool, substantially as described.

2. In a punching-machine, the main frame and the levers B and E and connections, in combination with a reciprocating plunger mounted in said frame and having a threaded opening, and a punching-tool having a threaded shank adjusted within said opening, substantially as herein described.

3. In a punching-machine, the frame A, having grooves formed in its front portion, a reciprocating two-part plunger sliding within 90 said grooves, and having a threaded semicircular groove, l, formed in each part, a punch passing through said plunger, and having a threaded shank engaging the threads in the grooves, whereby the punch is adjusted, and 95 screws for securing the two parts of the plunger together, substantially as described.

4. In a punching-machine, a main frame, in combination with a plunger formed in two sections, each section of which is provided 100 with a semicircular threaded opening, and a punching-tool having a punching-face and an integral threaded shank engaging the threads in the grooves, whereby the tool is adjusted, substantially as described.

Witnesses: CHESTER ROACH.
